[57] **CLAIM**

The ornamental designs for a combined article holder and rope cinch therefor, as shown and described.

DESCRIPTION

FIG. 1 is a perspective view of a combined article support and rope cinch therefor showing my new design; FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a perspective view of a second embodiment of the design shown in FIG. 1;

FIG. 9 is a perspective view of a third embodiment of the design shown in FIG. 1;

FIG. 10 is an enlarged detailed perspective view of the rope cinch clasp detached from the rope cinch for clarity of illustration only;

FIG. 11 is a left side elevational view thereof;

FIG. 12 is a right side elevational view thereof;

FIG. 13 is a bottom plan view thereof; and

FIG. 14 is a top plan view thereof.

FIG. 6

FIG. 7
